United States Patent Office

Des. 228,203
Patented Aug. 21, 1973

228,203

RADIO

Carl Yurdin, Port Washington, N.Y., assignor to
Harman-Kardon Incorporated, Plainview, N.Y.

Filed Aug. 10, 1971, Ser. No. 170,673

Term of patent 14 years

Int. Cl. D14—03

U.S. Cl. D56—4 B

FIG. 1 is a front and right side perspective view of a radio, showing my new design;

FIG. 2 is a front elevational view;

FIG. 3 is a rear elevational view; and

FIG. 4 is a left side elevational view, the right side being substantially a mirror image thereof.

I claim:

The ornamental design for a radio, as shown and described.
